UNITED STATES PATENT OFFICE.

ROLLIN C. LEWIS, OF STAMFORD, CONNECTICUT, ASSIGNOR TO THE YALE & TOWNE MANUFACTURING COMPANY, OF STAMFORD, CONNECTICUT.

TIME-CONTROLLED DEAD-LOCKING DEVICE.

1,337,083.

Specification of Letters Patent. Patented Apr. 13, 1920.

Application filed July 29, 1919. Serial No. 314,100.

To all whom it may concern:

Be it known that I, ROLLIN C. LEWIS, a citizen of the United States, and a resident of Stamford, in the county of Fairfield and 5 State of Connecticut, have invented certain new and useful Improvements in Time-Controlled Dead-Locking Devices; and I do hereby declare the following to be a full, clear, and exact description of the invention, such as will enable others skilled in the 10 art to which it appertains to make and use the same.

This invention relates to an improvement in time controlled dead lock, designed more 15 particularly for use on store doors, the object being to provide a lock so constructed and arranged in connection with time mechanism, that the door may be locked for a predetermined time against all keys of the 20 lock except a key, herein referred to as a master key, in connection with a second key herein referred to as a clerk's key, and at the expiration of such time be transformed by the automatic time mechanism into a lock 25 operable by the clerk's key alone.

A further object is to provide a lock of the character above referred to with a bolt adapted to be projected at either side of the 30 lock case so that the lock may be used at either side of the door.

With these and other objects in view my invention consists broadly in a bolt, a dead locking device controlled by time mechanism, key mechanism for shifting the bolt 35 and key mechanism for disengaging the dead locking device whereby the bolt will be free to be actuated by the bolt shifting mechanism.

My invention further consists in the parts 40 and combination of parts and in details of construction as will be more fully explained and pointed out in the claims.

In the accompanying drawings; Figure 1 is a view in rear elevation of the lock, the 45 cover plate of the casing being removed and shown at the side; Fig. 2 is a similar view with the time mechanism removed; Fig. 3 is a view in transverse vertical section; Fig. 4 is a detached view of the driving wheel of 50 the time mechanism and the lever actuated thereby for withdrawing the bolt dead-locking means, and Fig. 5 is a view in vertical section through the bolt and locking and deadlocking means for the latter.

10 represents a lock casing adapted to be

secured to the inner face of the door, and 11 is the cover plate of the casing detachably secured to the latter by nuts 12 screwed onto the posts 13 which are secured to the casing and pass through holes in the cover plate. 60 The cover plate is provided with a glass covered peep opening 14, through which the dial numerals of the time mechanism may be seen from the rear, and with an opening 15 for the key for winding up the time mechanism. 65

The details of the time mechanism form no part of my invention, hence only such features thereof as coöperate with my lock are shown and herein referred to. 70

The bolt 16 is mounted in openings in the opposite sides of the lock casing so that either end thereof may be the locking end of the bolt, thus adapting it for right and left hand doors, and it may be shifted from its locked to its unlocked position and vice versa, when not deadlocked, by the cam 17 of the pin tumbler key lock 17^a which is actuated by the clerk's key. This bolt is provided on the top edge with a slot 18 the 80 side walls of which are parallel for a short distance and then widen out, the side walls 19 below the parallel portions being inclined as shown to be engaged by the cam 17 for shifting the bolt longitudinally from its 85 locked to its unlocked position.

Mounted in the housing 20 at the upper part of the casing 10, and above the bolt 16, are the spring pressed dogs 20 and 21, one of which enters the slot 18 for locking the 90 bolt when the latter is projected at one side of the casing 10, and the other coöperates with said slot for locking the bolt in its unlocked position.

When the bolt is projected at the left, as 95 in full lines in Fig. 1, the dog 20 enters slot 18 for locking the bolt in its projected position, and is lifted and removed from the said slot by its contact with the end of cam 17, which as before explained is actuated by the 100 clerk's key. When the bolt is retracted the dog 21 falls into the slot 18 and holds the bolt against movement until actuated by the clerk's key. When the locking end of the bolt is at the opposite side of the casing, as 105 shown in dotted lines in Fig. 1, the dog 21 enters the slot 18 and retains the bolt in its locked position, while the dog 20 locks it when retracted.

It will thus be seen that the dogs 20 and 110

21 operate respectively to dog the bolt in its projected and retracted position, hence when the full line position, Fig. 1, represents the locking position of the bolt, the latter will be dogged in its projected position by the dog 20, and be dogged in its retracted position by the dog 21, and when the dotted line position, Fig. 1, represents the locking position of the bolt, the latter will 10 be dogged in its projected position by the dog 21 and in its retracted position by the dog 20, the dogs riding on the top of the bolt when the latter is at an intermediate position. These dogs project into the slot 15 18 in the bolt sufficiently to be engaged and lifted by the cam 17 in its movements to retract or project the bolt.

The bolt is also provided on its upper surface with two recesses 22-23, the recess 23 being adapted to receive the lower end of the 20 time mechanism actuated plunger 24 when the bolt is used at one side of the lock for deadlocking the bolt, and the other recess is adapted to receive the plunger 24 when 25 the locking position of the bolt is at the opposite side of the casing, the recess not in use when the lock is applied to a door being closed by a screw plug 25, the upper surface of which is flush with the top surface of 30 the bolt so as to permit the plunger 24 to ride freely thereon. The slot 18 is located adjacent the rear face of the bolt, and in rear of the plane of the recesses 22 and 23 so that the path of movement of the said 35 recesses is not in the plane of the plunger 21.

In applying the lock to a door, if the full line position, Fig. 1 of the bolt, be its locking position, recess 22 will be closed by the plug 25, whereas if the dotted line position, 40 be its locking position, the screw plug would be applied in recess 23 and recess 22 be left open.

The plunger 24 is normally held in contact with the bolt by a spring, and it is provided in its rear face with an opening for 45 the pin 26 on the rod 27, the plunger housing having an elongated slot 27 for the passage and movement of the pin 26. This rod is bent to clear the time mechanism of the lock and is connected at its lower end by 50 pin 28, to the lever 29 pivoted to the plate 30 of the time mechanism of the lock. This lever is pivoted intermediate its ends and its free end projects upwardly and terminates 55 in a flat surface 31 which is in the path of movement of pin 32 on the driving wheel 33 of the time mechanism, so that during the part revolution of this wheel, the pin 32 will contact with the end of lever 60 29 and turn the latter in a direction to lift rod 27 and the plunger 24 connected with the said rod.

The lock 34 is also of the pin tumbler type, and is designed to be actuated by the 65 master key. It is provided with a cam 35,

which when turned, is adapted to engage pin 28 on rod 27 and move the latter upwardly thus raising the plunger 24.

The driving wheel 33 of the time mechanism carries a dial numbered to represent 70 hours, and a pointer 36 is located over the dial and visible through the peep hole in the casing. This dial may be set by the winding key to actuate the plunger 24 at any time within a certain period, and until that 75 period has been reached the lock will be deadlocked against all keys but the master key, which as above explained may be used to lift the plunger 24 at any time.

The time mechanism of the lock may be 80 designed to run for any reasonable length of time, and it may be set to actuate the dead locking plunger after the expiration of any number of hours or fractions thereof within its limit, and until such time has 85 elapsed the lock will be positively deadlocked against all keys but the master key, so that it will be impossible for one having a clerk's key to unlock the door while the latter is deadlocked by the time mechanism, 90 but the deadlocking plunger may be withdrawn from the bolt at any time by the insertion and turning of a master key in its lock and holding the deadlocking plunger elevated by the master key while the bolt 95 is retracted by a clerk's key in the usual manner.

In applying the lock to a door, the screw plug 25 should be inserted in its proper recess the other recess being left open to receive the deadlocking plunger, and if it should be desired to thereafter use the other end of the bolt as the locking end, the plug can be removed and secured in the other recess. 100

With a lock so constructed the time lock would be set, say Saturday afternoon to release the dead lock at eight o'clock Monday morning. When that hour is reached the time mechanism of the lock will lift the 110 deadlocking plunger thus disengaging the latter from the bolt and holding it out of engagement until the time mechanism has been reset. After the plunger has been withdrawn by the time mechanism, the bolt 115 may be retracted by the clerk's key and the door opened. If however, it should be necessary to open the door prior to the time the automatic mechanism has been set to withdraw the deadlocking plunger, it may be 120 done by a master key and a clerk's key as explained, the master key operating to withdraw the deadlocking plunger and the clerk's key retracting the bolt.

It is evident that many slight changes 125 might be resorted to in the relative arrangement of parts shown and described without departing from the spirit and scope of my invention. Hence I would have it understood that I do not wish to confine myself to 130

the exact construction and arrangement of parts shown and described, but

Having fully described my invention what I claim as new and desire to secure by Letters-Patent, is:—

1. In a lock, the combination of a bolt, key mechanism for actuating same, time controlled mechanism for deadlocking the bolt against said key mechanism, and a master key mechanism for disengaging the time controlled deadlock from the bolt whereby the latter may then be actuated by its key mechanism.

2. In a lock, the combination of a bolt, time controlled means for deadlocking the bolt, key mechanism for actuating the bolt when the latter is not deadlocked and independent key mechanism for withdrawing the deadlocking means prior to the time set for the release of the bolt by the time mechanism thus permitting the bolt to be retracted by its key mechanism.

3. In a lock, the combination of a bolt, dogging means, and deadlocking means for the bolt, key mechanism for actuating the dogging means, time mechanism for disengaging the deadlocking means, and key mechanism independent of the time mechanism for disengaging the deadlocking means thus leaving the bolt free to be retracted by its key mechanism.

4. In a lock, the combination of a bolt, dogging means for the same, key mechanism for actuating the dogging means and bolt, a deadlocking plunger, time mechanism for disengaging the deadlocking plunger from the bolt, and second key mechanism for disengaging the deadlocking plunger prior to the time set for the operation of the time mechanism.

5. In a lock, the combination of a casing, a bolt adapted to be projected at either side of the latter whereby the lock may be used on a right or left hand door, two dogs one of which dogs the bolt when projected and the other when retracted, and means for deadlocking the bolt in each of its positions.

6. In a lock, the combination of a casing, a bolt adapted to be projected at either side of the latter whereby the lock may be used at either side of a door and two dogs one of which dogs the bolt in locking position and the other dogs the bolt when retracted, and which operate reversely when the locking position of the bolt is reversed.

7. In a lock, the combination of a lock casing, a bolt adapted to be projected at either side of the casing and provided with

two recessed seats, a time controlled deadlocking plunger adapted to enter one of said seats and a removable plug for closing the other seat.

8. In a lock, the combination of a lock casing, a bolt adapted to be projected at either side of the casing and provided with two recessed seats, one of which is closed by a removable plug, a deadlocking plunger adapted to enter the open seat for deadlocking the bolt, key mechanism for actuating the bolt when the latter is not deadlocked, and time mechanism for withdrawing said plunger at a predetermined time.

9. In a lock, the combination of a lock casing, a bolt adapted to be projected at either side thereof and provided with two recessed seats, a removable plug closing one of said seats, a deadlocking plunger adapted to enter the open seat for deadlocking the bolt, key mechanism for actuating the bolt when the latter is not deadlocked, and a second key mechanism for disengaging the plunger from the bolt so as to permit the bolt to be actuated by the first mentioned key mechanism.

10. In a lock, the combination of a lock casing, a bolt adapted to be projected at either side thereof and provided with two recessed seats either of which may be closed by a removable plug, a deadlocking plunger adapted to enter the open seat for deadlocking the bolt, key mechanism for actuating the bolt when the latter is not deadlocked, time mechanism connected with the plunger for withdrawing it from its seat in the bolt at a predetermined time and a second key mechanism for withdrawing the said plunger from the bolt prior to the operation of the time mechanism.

11. In a lock, the combination of a bolt, a deadlocking device for same, time controlled mechanism for disengaging the deadlocking device from the bolt, key mechanism for actuating the time controlled mechanism whereby the bolt may be released from the deadlock prior to the time set for its release by the time mechanism and independent means for retracting the bolt after the withdrawal of the deadlocking device.

In testimony whereof I have signed this specification in the presence of two subscribing witnesses.

ROLLIN C. LEWIS.
